CLAIM

The ornamental design for a five spoke wheel, as shown and described.

DESCRIPTION

FIG. 1 shows a front view of my design for a five spoke wheel;

FIG. 2 shows a front perspective view thereof; and,
FIG. 3 shows a side perspective view thereof with all sides around being identical as the wheel is symmetrical.

The back view forms no part of the invention.

The five spoke wheel is shown on an enlarged scale in FIG. 3.
